UNITED STATES PATENT OFFICE.

HARRY C. FOSTER, OF CONNERSVILLE, INDIANA, ASSIGNOR TO INDIANA LAMP COMPANY, OF CONNERSVILLE, INDIANA, A CORPORATION.

LATCH FOR HEADLIGHTS.

Application filed June 13, 1921. Serial No. 477,153.

To all whom it may concern:

Be it known that I, HARRY C. FOSTER, a citizen of the United States, and a resident of Connorsville, county of Fayette, and 5 State of Indiana, have invented a certain new and useful Latch for Headlights; and I do hereby declare that the following is a full, clear, and exact description thereof, reference being had to the accompanying 10 drawings, in which like numerals refer to like parts.

This invention relates to a lamp construction, and particularly to the type of lamps employed as headlights for vehicles, wherein 15 the lamp closure or lens rim is detachable from the casing.

The main feature of the invention relates to the locking means for positively securing the lamp closure or lens rim to the casing by 20 yielding means, whereby it may be removed by imparting thereto the usual rotating movement. This is accomplished by means of a spring-pressed latch normally held in locking position under spring tension, the 25 rim being removed by overcoming said spring tension, causing the release of the latch.

The full nature of the invention will be understood from the accompanying drawings 30 and the following description and claims.

In the drawings, Fig. 1 is a side elevation of a lamp casing with a portion of the rim broken away. Fig. 2 is a front elevation of 35 a portion of the lamp with a part of the rim removed. Fig. 3 is a side elevation of a portion of the casing with the rim removed, showing a modified form. Fig. 4 is a front elevation of a portion of the modified form.

40 In the drawings there is shown the usual lamp casing 10 having an annular bead 11 from which the annular flange 12 projects. The lamp closure or lens rim 13 is adapted to fit snugly over the flange 12 in the usual manner, the lens 14 being mounted in said rim.

45 The flange 12 is provided with a peripheral passageway 15, there being about three or four such passageways spaced around the periphery. The forward edge of the flange is depressed at 16 to provide an opening to said passageways through which the pins 17 may pass, said pins 17 extending inwardly and radially from the lamp closure or lens

55 rim 13. The rim is mounted on the lamp casing in the usual manner, by placing it in position so that said pins are opposite the depressed portions 16, whereby the rim may be forced over the flange 12, abutting the bead 11, after which the rim is rotated 60 slightly so that the pins 17 move to the end of the passageways 15 opposite the depression 16. This manner of mounting the rim is old and well known in the art.

For locking the pin 17 in the slot 15, there 65 is a latch 18 which is pivoted between its ends to the flange 12 by the rivet 19, and provided with a bearing plate 20 extending inwardly therefrom through the slot 21 for relieving the rivet 19 from undue strain 70 placed on the latch. The latching end is provided with the pin engaging notch 22, and the opposite end is provided with a projection 23 adapted to extend into the yielding spiral spring 24. This end of the latch 75 has a laterally bent tail 25 which engages the opposite or inner surface of the flange 12, extending through an opening 26 therein, for guiding the latch in its movement. The spring is seated on a suitable projection in 80 the opening 26 of the flange 12, and exerts a normal outward pressure against the latch so as to exert an inward pressure on the latching end, whereby the pin 17 can only be released from said latch when the spring is 85 compressed. This latch prevents the free 90 rotary movement of the rim so that vibration of the lamp will not cause the rim to turn until the pin passes through the depression 16, allowing it to fall from the casing.

In the modified form shown in Figs. 3 and 4, the latch 118 is provided with the notch 122 in which the rim pin 117 is adapted to seat. The latch is pivoted to the flange at 119 and is then bent inwardly, extending 95 through the slot 126 in said flange, so that the tail 125 extends adjacent the inside of the flange 12, the projection 123 seating in the spring 124. Said spring is supported on a plate 121 secured to said flange and extends laterally therefrom. The functioning and principle of the latch disclosed in the modified forms is substantially the same as that above described.

100 The invention claimed is:

105 1. A lamp construction, in combination with a casing member, and a closure member for said casing, of means for securing

said closure member thereon, including a suitable opening in said last mentioned member.

5 provided with a notch in one end thereof adapted to engage and hold said pin, and a compression spring mounted between the opposite end of said lever and the member upon which it is mounted for normally 10 maintaining the notched end thereof in engagement with said pin, whereby said pin may be moved out of engagement with said lever upon the compression of said spring.

2. A lamp construction, in combination 15 with a casing member, and a closure member for said casing, of means for securing said closure member thereon, including a passageway in one of said members, a pin on the other member adapted to extend into 20 said passageway, a substantially straight lever fulcrumed between its ends to the passageway bearing member having one end thereof in position to engage said pin, and yielding means mounted at the other end 25 of said lever on the opposite side of said fulcrum from the engaging end thereof for yieldingly maintaining it in engagement with said pin.

3. A lamp construction, in combination 30 with a casing member, and a closure member for said casing, of means for securing said closure member thereon, including a passageway in one of said members, a pin on the other member adapted to extend into 35 said passageway, a lever fulcrumed to the passageway bearing member having one end thereof in position to engage and retain said pin, yielding means mounted at the other end of said lever for yieldingly maintaining it in engagement with said pin, and a bearing plate adjacent the fulcrum point of said lever adapted to extend through a

4. A lamp construction, in combination 45 with a casing member, and a closure member for said casing, of means for securing said closure member thereon, including a passageway in one of said members, a pin on the other member adapted to extend into 50 said passageway, a lever fulcrumed to said passageway bearing member having a notch in one end thereof adapted to engage and hold said pin, and a spiral compression spring mounted between the opposite end of 55 said lever and said passageway bearing member for normally maintaining the notched end of said lever in engagement with said pin, whereby said pin may be moved out of engagement with said lever 60 and out of passageway upon the compression of said spring.

5. A lamp construction, in combination 65 with a casing member, and a closure member for said casing, of means for securing 70 said closure member thereon, including a passageway in one of said members, a pin on the other member adapted to extend into said passageway, a lever having a notched end adapted to engage said pin, means near 75 the center of said lever for pivotally securing it to said passageway bearing member, and a compression spring positioned between the other end of said lever and said passageway bearing member for normally 80 forcing the notched end thereof into engagement with said pin, the spring engaged end of said lever extending through an opening in said last mentioned member to the opposite side thereof so as to provide a guide for the movement of said lever.

In witness whereof, I have hereunto affixed my signature.

HARRY C. FOSTER.
